LAYING MACHINE GUIDE FOR WARP
KNITTING MACHINES

Emil Herbert Wirth, Hartmannsdorf, near
Chemnitz, Germany, assignor to the Firma
Emil Wirth Wirkmaschinenfabrik, Hartmanns-
dorf, near Chemnitz, Germany

Application April 5, 1938, Serial No. 200,233
In Germany October 30, 1937

4 Claims. (Cl. 66—86)

The present invention relates to a guide of a laying machine for warp knitting machines.

The sliding bushings for the laying machines used hitherto in connection with warp knitting machines consist of two parts one of which is fixed in the guide bar holder, whereas the other is connected by means of screws to the fixedly arranged part.

Besides the fact, that the loosening of the bushings for the purpose of withdrawing the guide of the laying machine is time consuming, these two-part sliding bushings still have the other great disadvantage, that they do not allow all parts of the bolts arranged in them to find the required complete rest.

Consequently, the high speeds used in modern warp knitting machines cause troubling noises and inaccuracies in the operation of the machine.

Now the purpose of the invention is to obviate the above mentioned disadvantages. This is obtained according to the invention by the fact, that the sliding bushings of the guide are formed as closed sleeves adapted to be withdrawn together with the guide, said sleeves may be fixed in the guide bar holder by means of web members or the like adapted to be held by screws.

In the accompanying drawing one construction according to the invention is shown by way of example.

30 In this drawing:

Fig. 1 is a front elevation of a guide of a laying machine according to the invention.

Fig. 2 is a side elevation of the arrangement according to Fig. 1 partly in section,

25 Fig. 3 is a front elevation of part of the arrangement disclosed in Fig. 1, showing the manner of loosening and fixing the sleeves, and

30 Fig. 4 is a side elevation of the holder which is fixed to the lever of the guide bar holder and supports the guide of the laying machine.

The guide of the laying machine consists in well known manner of a frame 1 carrying the bar 2 supporting the guides 3.

Journalled in the frame 1 are hollow bolts 4 and 5 by means of which the guide of the laying machine is connected to the lever 6 of the guide bar holder.

The holder 1 is, as may be seen from Fig. 2, fixed in any suitable manner to the lever 6 of the guide bar holder. As clearly shown in Figures 2 and 4, bearing sleeves 8 and 9 the diameter of which is considerably greater than that of the holder bolts 4 and 5 are provided at the ends of the holder 1. The bearing sleeves 8 and 9 are 55 provided with a slot 10 and 11 respectively ex-

tending over their entire length. The width of the slots 10 and 11 is somewhat larger than the diameter of the hollow bolts 4 and 5.

Mounted upon each of the hollow bolts 4 and 5 is, according to the invention, a sliding bushing 12 formed as a sleeve having a knurled head 13. The inner diameter of the bushing or sleeve 12 corresponds to the outer diameter of the holder bolts 4 and 5. The outer diameter of the sleeve 12 is equal to the inner diameter of the bearing sleeves 8 and 9.

Each of the sliding sleeves 12 is provided on its outer surface with a flattened portion 14. A web member 16, consisting preferably of resilient material, is swingably connected to the holder 1 by means of a screw 15. The ends of the web member 16 may be pressed against the flattened portion 14 of the two sliding sleeves 12.

If the guide of the laying machine occupying the operative position shown in Fig. 1 is to be withdrawn from the warp knitting machine, the screw 15 is loosened and the web member 16 brought into the position shown in Fig. 3, whereupon the sliding sleeves 12 may be withdrawn from the bearing sleeves 8 and 9 by exerting a pull on the head 13. Thereupon the hollow bolts 4 and 5 of the frame 1 may readily be moved through the longitudinal slots 10, 11 of the bearing sleeves 8 and 9, that is to say, the guide of the laying machine may now without difficulty be withdrawn from the warp knitting machine.

If now the guide of the laying machine is to be inserted again into the warp knitting machine, the bolts 4 and 5 are first moved through the longitudinal slots 10, 11 into the bearing sleeves 8, 9 in which they are sufficiently held until the two sliding sleeves 12 are shifted into the bearing sleeves 8, 9, the web member 16 has been swung around the screw 15 into the position shown in Fig. 1, and the screw 15 itself has been tightened.

What I claim is:

1. A support for a guide for a laying machine for warp knitting machines comprising a frame carrying said guide, closed sleeves slidably mounted upon a portion of said frame, a holder connected to the guide bar holder of said laying machine, sleeves each capable of receiving one of said closed sleeves carried by said holder and each having a longitudinal slot formed through one entire side thereof for receiving said portion of the frame therethrough and means for retaining said closed sleeves in their respective slotted sleeves.

2. A support for a guide of a laying machine for warp knitting machines comprising a frame carrying said guide, a pair of hollow bolts mounted on said frame, a pair of closed sleeves each slidably mounted upon one of said hollow bolts, a holder connected to the guide bar holder of said laying machine, each end of said holder being in the form of a sleeve for receiving one of said closed sleeves, each of said holder sleeves having a longitudinal slot formed through one entire side thereof for receiving one of said hollow bolts therethrough and means for retaining said closed sleeves in their respective holder sleeves. 5
3. A support for a guide of a laying machine for warp knitting machines comprising a frame carrying said guide, a pair of hollow bolts mounted on said frame, a pair of closed sleeves each slidably mounted upon one of said hollow bolts, a holder connected to the guide bar holder of said laying machine, each end of said holder being in the form of a sleeve for receiving one of said closed sleeves, each of said holder sleeves having a longitudinal slot formed through one 10 entire side thereof for receiving one of said hollow bolts therethrough and means for retaining said closed sleeves in their respective holder sleeves. 10
3. A support for a guide of a laying machine for warp knitting machines comprising a frame carrying said guide, a pair of hollow bolts mounted on said frame, a pair of closed sleeves each slidably mounted upon one of said hollow bolts, a holder connected to the guide bar holder of said laying machine, each end of said holder being in the form of a sleeve for receiving one of said closed sleeves, each of said holder sleeves having a longitudinal slot formed through one 15 entire side thereof for receiving one of said hollow bolts therethrough, each of said closed sleeves being provided with a flattened portion and a web pivotally mounted on said holder and being adapted to have its ends resiliently pressed against said flattened portions of said closed sleeves to hold said closed sleeves in said bearing sleeves. 20
